UNITED STATES PATENT OFFICE.

CHARLES G. TERFLER, OF CHICAGO, ILLINOIS.

AUTOMOBILE LOCK-SWITCH.

1,152,062.

Specification of Letters Patent. Patented Aug. 31, 1915.

Application filed March 31, 1913. Serial No. 757,980.

To all whom it may concern:

Be it known that I, CHARLES G. TERFLER, a citizen of the United States, residing at Chicago, in the county of Cook and State 5 of Illinois, have invented certain new and useful Improvements in Automobile Lock-Switches, of which the following is a specification.

My invention relates to new and useful 10 improvements in electric switches and the object of my invention is to provide an electric switch in which the movable switch member is inclosed in a casing and its movement controlled by a lock and key.

15 A further object of my invention is to provide a switch of the above described character peculiarly adapted for use in electric ignition systems for automobiles and other engines which are commonly started 20 upon a battery current and later operated upon a magneto current, the switch being employed in selectively opening or closing the battery circuit and consequently closing or opening the magneto circuit.

25 A further object of my invention is therefore to so construct the switch that it may be readily secured to the dash or other suitable portion of a self-propelled vehicle. And a still further object of my invention 30 is to so construct the casing of the switch that its face cap or cover may be removed when necessary to permit repairs or adjustment of parts.

35 With these and other objects in view, my invention will be more fully described, illustrated in the accompanying drawing, and then specifically pointed out in the claims which are attached to and form a part of this application.

40 In the drawing: Figure 1 is a front elevation of my improved switch, the switch operating plate carried by the key controlled lock being shown in dotted lines; Fig. 2 is a section on the line 2—2 of Fig. 3, showing 45 the interior construction of the switch; Fig. 3 is a section on the line 3—3 of Fig. 1, showing further details of switch construction; Fig. 4 is a perspective view of the complete switch; Fig. 5 is a fragmentary 50 sectional view of the swinging terminal of the movable switch member.

Corresponding and like parts are referred to in the following description and indicated in all the views of the drawing by the same 55 reference characters.

The preferred embodiment of my inven-

tion primarily includes a switch mechanism indicated as a whole by the numeral 10 inclosed in a casing 11 and operable by a switch operating plate 12 carried by a key controlled lock 13. More specifically the casing 11 comprises a cylindrical body or shell 14, preferably formed of metal and normally open at both ends, said body member being provided at its inner end with inwardly directed, radial lugs 15 arranged at spaced intervals and perforated as at 16 to receive screws by means of which the casing may be secured with its inner end against an automobile dash or other support. The 70 casing 11 further comprises a cap or cover 17 which engages over the outer end of the body portion of the casing and which is provided with a peripheral flange 18 which bears about the outer portion of said body 75 member, this flange having diametrically disposed bayonet slots 19 arranged to receive pins 20 carried by the casing and by means of which the relative movement of the two casing members is limited.

80 The switch mechanism 10 includes a base or support 21 formed of any suitable insulating material such as fiber or vulcanized rubber and proportioned to extend transversely across the intermediate portion of 85 the main casing 14 in which position it is secured by a plurality of spaced screws 22 passed inwardly through the walls of said casing member and into the edge portion 90 of the base or plate 21. The edge portions of this base are cut-away in alignment with the ears or lugs 15 of the inner casing member as shown at 23 to permit the insertion of a screw driver for securing the switch in place. This base 21 carries three symmetrically arranged binding posts 24, 25 and 26, the former of which serves as the pivot point for the swinging switch arm 27, while the latter are provided at their outer ends with contact terminals 28 and 29, respectively, adapted to engage the contact 30 carried by the free end of the switch arm 27. The base also carries pins 31 and 32 positioned one adjacent each of the binding posts 25 and 26 to serve as stops and limit the movement of the switch arm. The switch arm is provided at its free end with a laterally directed stud 33 about which is mounted a sleeve 34 of insulating material, this sleeve being free to turn about the stud 33, but being held against disengagement therefrom by an enlarged head 35 formed

upon the free end of the stud. As the above described arrangement of switch contacts and switch blade is well known in the art, no further description of its construction or 5 operation is necessary.

The cap or cover 17 of the casing is lined with a disk or plate 36 of insulating material and this cap and plate are provided centrally with alined openings to receive the 10 body of a plug lock of the usual or any conventional type, this lock being firmly clamped in place by a nut 37 threaded upon the inner end of the lock body and engaging against the inner face of the plate 36, the 15 outer end of the lock body being provided with a peripheral shoulder 38 which engages against the outer face of the cap. The key post 39, which is adapted to receive a key 40 and which may be turned by said key, extends 20 by its inner end beyond the body of the lock and carries the switch actuating plate 12, this plate being secured to the inner end of the post by screws 41 passed through a washer 42 and the plate 12 and into the key 25 post. It will therefore be apparent that any turning of the key in the lock will cause a corresponding turning of the switch actuating plate 12. This plate, as best shown in Figs. 1 and 2 of the drawings, is eccentrically 30 mounted and is cut-away at one side as shown at 43 to receive the insulated stud of the movable switch member. It will therefore be seen that any rotation of this switch plate about the centrally located key post as an axis will cause a corresponding swinging of the switch arm 27 to move the same into engagement with either the contact 28 or 29 as the case may be. The switch operating 35 plate is further cut-away at substantially opposite points as shown at 44 and 45 to permit the positioning of the plate and casing cover, the inner or main casing member being provided at diametrically opposite points with inwardly extending lugs 46 which pass 40 through the cut-away portions of the plate as the cover is being applied and beneath which the edge portions of the plate engage when the cover is in position.

In applying the cover, the key is inserted 45 in the lock and the lock actuating plate and cover so moved as to bring the cut-away portions 44 and 45 into alinement with the lugs 46 and the cut-away portion 43 into alinement with the stud of the switch arm, which latter has been previously swung to such a 50 position as to permit this three-point adjustment. The cover or cap is then applied and partially rotated to lock the pins 20 in the slots 19. When so adjusted the peripheral edge portions of the switch actuating plate engage beneath the lugs 46 and lock the cover against outward movement, there then being no strain upon the pins 20. At 55 the same time, the plate may be readily swung through the action of the key to move

the switch member 27 from one position to another to selectively close the circuits.

It should be noted that the lock 13 is clamped in such a manner in the cover that the lock, as a whole, cannot be turned except by turning the cover and it will of course be apparent that this being the case the locking plate 12 will, unless the key is in the lock, turn with the cover. If then when the lock and casing are being assembled the casing is so applied that the pins seat in the body portion of the slot and with the casing held in this position the key is turned to swing the moving contact arm from engagement with the contact 25 to an intermediate position between the contacts 25 and 26 and the cover of the casing then turned to seat the pins in the lateral extensions of the slot, the key and therefore the locking plate being held against turning in the meantime, it will be clear that upon removal of the key the cover will be locked upon the casing providing the lateral extensions of the slots are too short to permit the reverse turning of the cover to a sufficient distance to close either circuit. Slots without the lateral extensions would be equally as effective except for the fact that during the customary use of the switch with the key in place, the cover would always be unlocked when one of the circuits was closed and might jar loose.

From the foregoing description it will be apparent that I have provided an extremely effective form of lock and key controlled electric switch and one which is peculiarly adapted for use in controlling the circuits in ignition systems for automobiles, this doing away with the employment of a pad lock or other device for fastening the switch arm in place as is now customary. The key may be left in the lock while the engine is running or as soon as the switch is set properly may be removed, as preferred. The casing may be of any suitable metal such as polished brass, or nickel ware and may be mounted at any convenient point on the vehicle.

I do not wish in any way to limit myself to the specific details of construction illustrated in the drawings and described in the above specification, as any changes, within the scope of the appended claims may be made at any time without in the slightest degree departing from the spirit of my invention.

Having thus described the invention, what is claimed as new is:

1. A lock switch including a casing, lugs formed on the interior of the casing, a switch mounted in the casing, a closure for the casing, a plug lock extending through the closure, means carried by the lock and engaging the switch for actuating the latter, said means also engaging the lugs to lock the closure against movement away from the cas- 120 125 130

ing, save in one position of the switch, and means permitting such movement of the closure when the switch is in such position and also limiting movement of the closure to 5 prevent bringing the switch to such position by movement of the closure.

2. A lock switch including a casing, lugs formed on the interior of the casing, a switch mounted in the casing, a closure for the casing, a plug lock extending through the closure, means carried by the lock and engaging the switch for actuating the latter, said means also engaging the lugs to lock the closure against movement away from the casing, save in one position of the switch, and means permitting such movement of the closure when the switch is in such position and also limiting movement of the closure to 15 prevent bringing the switch to such position by movement of the closure, said means limiting turning of the closure with respect to 20 the casing.

3. A lock switch including a casing, lugs formed on the interior of the casing, a switch mounted in the casing, a closure for the casing, a plug lock extending through the closure, means carried by the lock and engaging the switch for actuating the latter, said means also engaging the lugs to lock the closure against movement away from the casing, save in one position of the switch, 25

and means permitting such movement of the closure when the switch is in such position and also limiting movement of the closure to 30 prevent bringing the switch to such position by movement of the closure, said means including a pin and slot connection between the casing and closure.

4. A lock switch including a casing, lugs formed on the interior of the casing, a switch mounted in the casing, a closure for the casing, a plug lock extending through the closure, means carried by the lock and engaging the switch for actuating the latter, said means also engaging the lugs to lock the closure against movement away from the casing, save in one position of the switch, and means permitting such movement of the closure when the switch is in such position and also limiting movement of the closure to 35 prevent bringing the switch to such position by movement of the closure, said means including the provision of a bayonet slot in the free edge of the closure, and a pin carried by the casing and seating in the slot. 40

In testimony whereof I affix my signature in presence of two witnesses.

CHARLES G. TERFLER. [L. s.]
